(57) **ABSTRACT**

A display panel includes a plurality of scan lines that receive scan signals, a plurality of data lines that receive data signals, lines that receive masking signals according to the scan signals, and a plurality of pixels respectively connected to the plurality of scan lines and the plurality of data lines. The error detection circuit receives the scan signals that are transmitted through the plurality of scan lines, and outputs an error detection signal based on the scan signals. Power is not supplied to the plurality of pixels when the error detection signal is at an activated level.

DISPLAY DEVICE FOR DETECTING AN ERROR IN SCAN LINES AND DRIVING METHOD THEREOF

CROSS-REFERENCE TO RELATED APPLICATION

Korean Patent Application No. 10-2016-0050341, filed on Apr. 25, 2016, in the Korean Intellectual Property Office, and entitled: "Display Device and Driving Method Thereof," is incorporated by reference herein in its entirety.

BACKGROUND

1. Field

The present disclosure herein relates to a display device and a driving method thereof, and more particularly, to a display device including an organic light-emitting diode (OLED) and a driving method thereof.

2. Description of the Related Art

An organic electroluminescence (EL) display device, one of display devices, displays an image by using an organic EL device (for example, OLED) that emits light by the recombination of electrons and holes. Since the organic EL display device is self-luminous and does not need an additional backlight unit, the organic EL display device is advantageous in terms of power consumption and has an excellent response time, viewing angle, contrast ratio, etc.

The organic EL device includes an anode, a cathode, and an organic light-emitting layer disposed therebetween. Electrons injected from the cathode and holes injected from the anode are recombined in the organic light-emitting layer to generate exitons, and the exitons emit light upon releasing energy. The organic light-emitting layer has a multilayer structure including an emission layer (EML), an electron transport layer (ETL), and a hole transport layer (HTL) in order to improve light-emitting efficiency by enhancing an electron/hole balance. The organic light-emitting layer may additionally include an electron injection layer (EIL), and an hole injection layer (HIL).

The organic EL device is driven by using power voltages ELVDD and ELVSS in addition to a pixel voltage according to an image signal. Accordingly, voltage lines or electrodes where these voltages are applied are provided in an organic EL display panel.

When the organic EL display panel is damaged due to an external pressure, and the like, a short circuit may be caused among a voltage line, a scan line, and a data line where the pixel voltage is applied, and thus an overcurrent may occur between a power supply circuit that provides the power voltages ELVDD and ELVSS and the organic EL display panel. The overcurrent may thus damage the organic EL display panel, and for example, the overcurrent may cause the organic EL display panel to be burnt.

SUMMARY

One or more embodiments provides a display device which includes a display panel having a plurality of scan lines to receive scan signals, plurality of data lines to receive data signals, and a plurality of pixels respectively connected to the plurality of scan lines and the plurality of data lines, and an error detection circuit to receive the scan signals transmitted through the plurality of scan lines, and to output an error detection signal based on the scan signals. Power is not supplied to the plurality of pixels when the error detection signal is at an activated level.

The error detection circuit may output the error detection signal based on the scan signals during light-emitting periods of the plurality of pixels.

The may include a scan driving circuit to provide the scan signals for the plurality of scan lines, wherein the scan driving circuit is electrically connected to one end of each of the plurality of scan lines, and the error detection circuit is electrically connected to the other end of each of the plurality of scan lines.

10 The scan driving circuit may provide the plurality of scan lines with the scan signals including a test pattern during the light-emitting periods of the plurality of pixels.

15 The scan signals may be a pulse signal with a predetermined frequency during the light-emitting periods of the plurality of pixels.

The scan signals may be pulse signals which are sequentially activated during the light-emitting periods of the plurality of pixels.

20 The error detection circuit may compare each of the scan signals with a reference voltage, and may activate the error detection signal depending on the comparison result.

The scan driving circuit and the error detection circuit may face each other with the display panel therebetween.

25 The scan signals may be pulse signals which are sequentially activated during the scan periods of the plurality of pixels.

30 The may include a plurality of masking lines corresponding to and extending parallel to each scan line, wherein the error detection circuit is to receive the masking signals transmitted through the plurality of masking lines, and output the error detection signal based on at least one of the scan signals or the masking signals.

35 Each of the masking signals may have a level complementary to the level of a corresponding scan signal among the scan signals during the light-emitting periods.

40 Each of the plurality of pixels may include a first transistor connected between a corresponding data line among the plurality of data lines and a first node, and having a gate electrode connected to a corresponding scan signal among the scan signals, a second transistor connected between the first node and a second node, and having a gate electrode connected to a corresponding masking signal among the masking signals, and a light-emitting circuit to receive a first power voltage and a second power voltage, and to emit light according to a voltage level of the first node.

45 The light-emitting circuit may include a first capacitor connected between the first power voltage and the second node, a second capacitor connected between the second node and a third node, a third transistor connected between the first power voltage and a fourth node, and having a gate electrode connected to the third node; and an organic light-emitting diode connected between the fourth node and the second power voltage.

50 The light-emitting circuit may include a fourth transistor connected between the third node and the fourth node, and having a gate electrode connected to a compensation signal.

55 The error detection circuit compares a sum of the scan signal and the masking signal corresponding to each other with the reference voltage, and activates the error detection signal depending on the comparison result.

60 The error detection circuit may output the error detection signal based on the masking signals during light-emitting periods of the plurality of pixels.

65 A driving method for a display device including a plurality of pixels connected to scan lines, the driving method including providing the scan lines with scan signals and/or masking lines with masking signals according to the scan

signals, comparing at least one of the scan signals or the masking signals with a reference voltage, and activating an error detection signal based on the comparison result.

The scan signals provided for the plurality of scan lines may be a pulse signal with a predetermined frequency.

The scan signals provided for the plurality of scan lines may be sequentially activated.

The masking lines may be connected to the pixels, and activating the error detection signal may include comparing a sum of the scan signal and the masking signal corresponding to each other with the reference voltage, and activating the error detection signal depending on the comparison result.

Activating the error detection signal may include dividing the scan signals into a plurality of scan signal groups, comparing a sum of the voltages of each of the plurality of scan signal groups with the reference voltage, and activating the error detection signal depending on the comparison result.

The driving method may further include stopping power supply to the pixels when the error detection signal is activated.

BRIEF DESCRIPTION OF THE DRAWINGS

Features will become apparent to those of skill in the art by describing in detail exemplary embodiments with reference to the attached drawings in which:

FIG. 1 illustrates a block diagram of a display device according to an embodiment;

FIG. 2 illustrates a pixel configuration provided for the display panel shown in FIG. 1, according to an embodiment;

FIG. 3 illustrates a timing diagram of, by way of example, an operation of the display device shown in FIG. 1;

FIG. 4 illustrates, by way of example, a configuration of an error detection circuit shown in FIG. 1, according to an embodiment;

FIGS. 5 and 6 illustrate timing diagrams of the operation of the error detection circuit shown in FIG. 4;

FIG. 7 illustrates a configuration of the error detection circuit shown in FIG. 1, according to another embodiment;

FIG. 8 illustrates a timing diagram of an operation of the error detection circuit shown in FIG. 7;

FIG. 9 illustrates a configuration of the error detection circuit shown in FIG. 1, according to another embodiment;

FIG. 10 illustrates a timing diagram of an operation of the error detection circuit illustrated in FIG. 9;

FIG. 11 illustrates a configuration of the error detection circuit of in FIG. 1, according to another embodiment;

FIG. 12 illustrates a timing diagram of an operation of the error detection circuit shown in FIG. 11;

FIG. 13 illustrates a timing diagram of an operation of the error detection circuit illustrated in FIG. 11, according to another embodiment; and

FIG. 14 illustrates a flowchart of an operation of the display device shown in FIG. 1.

DETAILED DESCRIPTION

Example embodiments will now be described more fully hereinafter with reference to the accompanying drawings; however, they may be embodied in different forms and should not be construed as limited to the embodiments set forth herein. Rather, these embodiments are provided so that this disclosure will be thorough and complete, and will fully convey exemplary implementations to those skilled in the art.

FIG. 1 is a block diagram illustrating a display device according to an embodiment. Referring to FIG. 1, a display device 100 includes a display panel 110, a signal control circuit 120, a data driving circuit 130, a scan driving circuit 140, an error detection circuit 150, a power voltage supply circuit 160, and a compensation control signal circuit 170.

The display panel 110 includes a plurality of scan lines SL1 to SLn, a plurality of data lines DL1 to DLm crossing the plurality of scan lines, and a plurality of pixels PX11 to PXnm in regions in which the plurality of scan lines and the plurality of data lines cross each other. The plurality of scan lines SL1 to SLn extend in a first direction DR1 from the scan driving circuit 140, and are sequentially disposed in parallel in a second direction DR2. The plurality of data lines DL1 to DLm extend in the second direction DR2 from the data driving circuit 130, and are sequentially disposed in parallel in the first direction DR1. The plurality of scan lines SL1 to SLn and the plurality of data lines DL1 to DLm are insulated from each other. A plurality of masking lines ML1 to MLn correspond respectively to the plurality of scan lines SL1 to SLn. Each of the plurality of masking lines ML1 to MLn is disposed adjacent to a corresponding scan line of the plurality of scan lines SL1 to SLn. Each of the plurality of pixels PX11 to PXnm receives, from the power voltage supply circuit 160, a first power voltage ELVDD and a second power voltage ELVSS. Each of the plurality of pixels PX11 to PXnm receives a compensation signal GC from the compensation control signal circuit 170.

The signal control circuit 120 receives image information ImS input from the outside and input control signals for controlling a display of the image information. The input control signal may include a horizontal synchronization signal Hsync, a vertical synchronization signal Vsync, and a main clock signal MCLK. The signal control circuit 120 outputs a first control signal CONT1 and an image data signal DATA which control the data driving circuit 130, a second control signal CONT2 for controlling the scan driving circuit 140, a third control signal CONT3 for controlling the power voltage supply circuit 160, a fourth control signal CONT4 for controlling the compensation control signal circuit 170, and a fifth control signal CONT5 for controlling the error detection circuit 150.

The data driving circuit 130 outputs data signals D1 to DM to drive the plurality of data lines DL1 to DLm in response to the first control signal CONT1 and the image data signal DATA from the signal control circuit 120.

The scan driving circuit 140 outputs scan signals S1 to Sn for driving the plurality of scan lines SL1 to SLn and masking signals M1 to Mn for driving the plurality of masking lines ML1 to MLn, in response to the second control signal CONT2 from the signal control circuit 120.

The error detection circuit 150 detects whether the display panel 110 is damaged, based on the scan signals S1 to Sn transmitted through the plurality of scan lines SL1 to SLn and the masking signals M1 to Mn transmitted through the plurality of masking lines ML1 to MLn, and outputs an error detection signal DET corresponding to the detection result. The error detection signal DET may be provided to the signal control circuit 120. The error detection circuit 150 may output the error detection signal DET based on either of the scan signals S1 to Sn or the masking signals M1 to Mn.

The power voltage supply circuit 160 supplies the first power voltage ELVDD and the second power voltage ELVSS required for the operation of the display panel 110, in response to the third control signal CONT3 from the signal control circuit 120.

The compensation control signal circuit 170 outputs the compensation signal GC in response to the fourth control signal CONT4 from the signal control circuit 120.

FIG. 2 illustrates a pixel configuration provided for the display panel shown in FIG. 1, according to an embodiment. Referring to FIGS. 1 and 2, a pixel PX_{ij} is connected to an i-th gate line GL_i and a j-th data line DL_j. The pixel PX_{ij} includes a first transistor T₁, a second transistor T₂, and a light-emitting circuit 111. The light-emitting circuit 111 includes a third transistor T₃, a fourth transistor T₄, a first capacitor C₁, a second capacitor C₂, and an organic light-emitting diode (OLED).

The first transistor T₁ is connected between the j-th data line DL_j and a first node N₁, and has a gate electrode connected to an i-th scan signal S_i. The second transistor T₂ is connected between the first node N₁ and a second node N₂, and has a gate electrode connected to an i-th masking signal M_i.

The first capacitor C₁ is connected between the first power voltage ELVDD and the second node N₂. The second capacitor C₂ is connected between the second node N₂ and a third node N₃. The third transistor T₃ is connected between the first power voltage ELVDD and a fourth node N₄, and has a gate electrode connected to the third node N₃. The fourth transistor T₄ is connected between the third node N₃ and the fourth node N₄, and includes a gate electrode connected to the compensation signal GC. The OLED has an anode terminal connected to the fourth node N₄, and a cathode terminal connected to the second power voltage ELVSS.

FIG. 3 is a timing diagram illustrating, by way of example, an operation of the display device illustrated in FIG. 1. Referring to FIGS. 1 to 3, a frame Ft during which an image is displayed on the display panel 110 includes a compensation period P₁, a scan period P₂, and a light-emitting period P₃.

When the compensation signal GC transitions to a low level during the compensation period P₁, the fourth transistor T₄ is turned on, so that the third node N₃ and the fourth node N₄ are connected. In this case, by adjusting the voltage levels of the first power voltage ELVDD and the second power voltage ELVSS, the voltages of the third node N₃ and the fourth node N₄ may be reset to predetermined voltages. In other words, the threshold voltage of the third transistor T₃ may be compensated by setting, to predetermined voltages, respective voltages of the gate electrode, a source electrode, and a drain electrode of the third transistor T₃.

The scan signals S₁ to S_n transition sequentially to a low level during the scan period P₂. The masking signals M₁ to M_n are maintained at a low level during the scan period P₂. The second transistor T₂ may maintain a turn-on state while the i-th masking signal M_i is at a low level. When the i-th scan signal S_i transitions to the low level, the first transistor T₁ is turned on, so that the i-th data signal D_i transmitted through the i-th data line DL_i is stored in the first capacitor C₁ and the second capacitor C₂.

When the second power voltage ELVSS transitions to a low level during the light-emitting period P₃, the OLED may emit light due to the voltages stored in the first capacitor C₁ and the second capacitor C₂.

During a predetermined test period P_t within the light-emitting period P₃, the scan signals S₁ to S_n transition to a high level and to a low level with a predetermined cycle. During the light-emitting period P₃, the scan driving circuit 140 outputs the masking signals M₁ to M_n, which have levels complementary to those of the scan signals S₁ to S_n. For example, when the i-th scan signal S_i transitions to the

low level, the i-th masking signal M_i transitions to the high level. Accordingly, even when the scan signal S_i transitions to the low level during the light-emitting period P₃, the data signal D_i received through the data line DL_i may be prevented from being transmitted to the second node N₂.

The test period P_t may be equal to or shorter than the light-emitting period P₃. The error detection circuit 150 illustrated in FIG. 1 outputs the error detection signal DET based on the scan signals S₁ to S_n and the masking signals M₁ to M_n during the test period P_t within the light-emitting period P₃.

FIG. 4 illustrates, by way of example, a configuration of an error detection circuit shown in FIG. 1, according to an embodiment. Referring to FIGS. 1 and 4, the error detection circuit 150 includes a detecting circuit 151 and a detection signal output circuit 152.

The detecting circuit 151 receives the scan signals S₁ to S_n and masking signals M₁ to M_n, and outputs detection signals SEN₁ to SEN_n. The detection signal output circuit 152 outputs the error detection signal DET in response to the detection signals SEN₁ to SEN_n when the fifth control signal CONT5 indicates the test period P_t.

More specifically, the detecting circuit 151 includes diodes D₁₁ to D_{1n} respectively connected to the scan signals S₁ to S_n, and diodes D₂₁ to D_{2n} respectively connected to the masking signals M₁ to M_n. The diodes D₁₁ to D_{1n} and the diodes D₂₁ to D_{2n} correspond to each other. Outputs of a pair of corresponding diodes among the diodes D₁₁ to D_{1n} and the diodes D₂₁ to D_{2n} are summed up and output as the detection signals SEN₁ to SEN_n. For example, the outputs of the diodes D₁₁ and D₂₁ are summed up and output as the detection signal SEN₁. The outputs of the diodes D_{1i} and D_{2i} are summed up and output as the detection signal SEN_i. The outputs of the diodes D_{1n} and D_{2n} are summed up and output as the detection signal SEN_n. The detection signal output circuit 152 deactivates the error detection signal DET to a low level when all the voltages of the detection signals SEN₁ to SEN_n are higher than the reference voltage VREF1. The detection signal output circuit 152 activates the error detection signal DET to a high level when at least one of the voltages of the detection signals SEN₁ to SEN_n is lower than the reference voltage VREF1.

FIGS. 5 and 6 are timing diagrams illustrating the operation of the error detection circuit illustrated in FIG. 4.

Referring to FIGS. 1, 4, and 5, the waveforms of the i-th scan signal S_i and the i-th masking signal M_i corresponding to the i-th scan signal S_i have a complementary relationship during the test period P_t when the pixels PX₁₁ to PX_{nm} and the scan lines SL₁ to SL_n of the display panel 110 are not damaged. Accordingly, the i-th detection signal SEN_i output from the detecting circuit 151 is maintained higher than the predetermined reference voltage VREF1. The detection signal output circuit 152 outputs the error detection signal DET having a low level since the i-th detection signal SEN_i has a level higher than the predetermined reference voltage VREF1.

Referring to FIGS. 1, 4, and 6, the waveforms of the i-th scan signal S_i and the i-th masking signal M_i corresponding to the i-th scan signal S_i do not have a complementary relationship during the test period P_t when at least one of the pixels PX₁₁ to PX_{nm} or the scan lines S₁ to S_n of the display panel 110 is damaged. In this case, the i-th detection signal SEN_i output from the detecting circuit 151 is maintained lower than the predetermined reference voltage VREF1. The detection signal output circuit 152 outputs the error detection signal DET having a high level since the i-th

detection signal SENi has a level lower than the predetermined reference voltage VREF1.

In response to the error detection signal DET at the high level, the signal control circuit 120 outputs the third control signal CONT3 such that the power voltage supply circuit 160 does not generate the first power voltage ELVDD and the second power voltage ELVSS. An operation of the display panel 110 is stopped when the power voltage supply circuit 160 does not generate the first power voltage ELVDD and the second power voltage ELVSS. Therefore, the display device 100 is protected against risks such as fire by preventing an overcurrent caused by a short circuit of the signal lines in the display panel 110.

FIG. 7 illustrates a configuration of the error detection circuit shown in FIG. 1, according to another embodiment. Referring to FIGS. 1 and 7, an error detection circuit 150_1 includes a detecting circuit 151_1 and a detection signal output circuit 152_1.

The detecting circuit 151_1 receives the masking signals M1 to Mn, and outputs detection signals SENM1 to SENMn/2. The detection signal output circuit 152_1 outputs the error detection signal DET in response to the detection signals SENM1 to SENMn/2 when the fifth control signal CONT5 indicates the test period Pt.

More specifically, the detecting circuit 151_1 includes diodes D31 to D3n respectively connected to the masking signals M1 to Mn. Outputs of a pair of adjacent diodes of the diodes D31 to D3n are summed up and output as the detection signals SENM1 to SENMn/2. For example, the outputs of the diodes D31 and D32 are summed up and output as the detection signal SENM1. The outputs of the diodes D3i and D3i+1 are summed up and output as the detection signal SENMi/2. The outputs of the diodes D3n-1 and D3n are summed up and output as the detection signal SENMn/2. The detection signal output circuit 152_1 deactivates the error detection signal DET to a low level when all the voltages of the detection signals SENM1 to SENMn/2 are higher than a reference voltage VREF2. The detection signal output circuit 152_1 activates the error detection signal DET to a high level when at least one of the voltages of the detection signals SENM1 to SENMn/2 is lower than the reference voltage VREF2.

FIG. 8 is a timing diagram illustrating an operation of the error detection circuit illustrated in FIG. 7.

Referring to FIGS. 1, 7, and 8, the i-th masking signal Mi and the (i+1)-th masking signal Mi+1 have the same waveform during the test period Pt when the pixels PX11 to PXnm and the masking lines ML1 to MLn of the display panel 110 are not damaged. Accordingly, the (i/2)-th detection signal SENMi/2 output from the detecting circuit 151_1 is maintained higher than the predetermined reference voltage VREF2. The i-th masking signal Mi is maintained at the low level when at least one of the i-th masking line MLi or the pixels PXi1 to PXim connected to the i-th masking line MLi is damaged. In this case, the detection signal output circuit 152_1 outputs the error detection signal DET having a high level since the (i/2)-th detection signal SENMi/2 has a level lower than the predetermined reference voltage VREF2.

FIG. 9 illustrates a configuration of the error detection circuit shown in FIG. 1, according to another embodiment. Referring to FIGS. 1 and 9, an error detection circuit 150_2 includes a detecting circuit 151_2 and a detection signal output circuit 152_2.

The detecting circuit 151_2 receives the scan signals S1 to Sn, and outputs detection signals SEN1 to SENSn/2. The detection signal output circuit 152_2 outputs the error detec-

tion signal DET in response to the detection signals SEN1 to SENSn/2 when the fifth control signal CONT5 indicates the test period Pt.

More specifically, the detecting circuit 151_2 includes 5 diodes D41 to D4n respectively connected to the scan signals S1 to Sn. Outputs of a pair of adjacent diodes of the diodes D41 to D4n are summed up and output as the detection signals SEN1 to SENSn/2. For example, the outputs of the diodes D41 and D42 are summed up and 10 output as the detection signal SEN1. The outputs of the diodes D4i and D4i+1 are summed up and output as the detection signal SENSi/2. The outputs of the diodes D4n-1 and D4n are summed up and output as the detection signal SENSn12. The detection signal output circuit 152_2 deactivates 15 the error detection signal DET to a low level when every voltage of the detection signals SEN1 to SENSn/2 is higher than a reference voltage VREF3. The detection signal output circuit 152_2 activates the error detection signal DET to a high level when at least one of the voltages of the detection signals SEN1 to SENSn/2 is lower than the reference voltage VREF3.

FIG. 10 is a timing diagram illustrating an operation of the error detection circuit illustrated in FIG. 9.

Referring to FIGS. 1, 9, and 10, the i-th scan signal Si and the (i+1)-th scan signal Si+1 have the same waveform during the test period Pt when the pixels PX11 to PXnm and the scan lines SL1 to SLn of the display panel 110 are not damaged. Accordingly, the (i/2)-th detection signal SENSi/2 20 output from the detecting circuit 151_2 is maintained higher than the predetermined reference voltage VREF3. The i-th scan signal Si is maintained at a low level when at least one of the i-th scan line SLi or the pixels PXi1 to PXim connected to the i-th scan line SLi is damaged. In this case, 25 the detection signal output circuit 152_2 outputs the error detection signal DET having a high level since the (i/2)-th detection signal SENSi/2 has a level lower than the predetermined reference voltage VREF3.

When the error detection circuit 150_2 detects the damage 30 of the display panel 110, the pixel PXij illustrated in FIG. 2 may not include the second transistor T2 and the display 110 in FIG. 1 may not include the masking lines ML1 to MLn.

FIG. 11 illustrates a configuration of the error detection circuit shown in FIG. 1, according to another embodiment. Referring to FIGS. 1 and 11, an error detection circuit 150_3 includes a detecting circuit 151_3 and a detection signal output circuit 152_3.

The detecting circuit 151_3 receives the scan signals S1 to Sn, and outputs detection signals SENSS1 to SENSSn/4. The detection signal output circuit 152_3 outputs the error detection signal DET in response to the detection signals SENSS1 to SENSSn/4 when the fifth control signal CONT5 indicates the test period Pt.

More specifically, the detecting circuit 151_3 includes 55 diodes D51 to D5n respectively connected to the scan signals S1 to Sn. Outputs of adjacent four diodes of the diodes D51 to D5n are summed up and output as the detection signals SENSS1 to SENSSn/4. For example, the outputs of the diodes D51, D52, D53, and D54 are summed 60 up and output as the detection signal SENSS1. The outputs of the diodes D5n-3, D5n-2, D5n-1, and D5n are summed up and output as the detection signal SENSSn/4. The detection signal output circuit 152_3 deactivates the error detection signal DET to a low level when all the voltages of the detection signals SENSS1 to SENSSn/4 are higher than a reference voltage VREF4. The detection signal output circuit 152_3 activates the error detection signal DET to a high

level when at least one of the voltages of the detection signals SENSS1 to SENSSn/4 is lower than the reference voltage VREF4.

FIG. 12 is a timing diagram illustrating an operation of the error detection circuit illustrated in FIG. 11.

Referring to FIGS. 1, 11, and 12, the scan driving circuit 140 provide the scan lines SL1 to SLn with the scan signals S1 to Sn that transition sequentially to a low level during the test period Pt. The voltage of the detection signal SENSS1, which is a sum of the scan signals S1, S2, S3, and S4, is maintained higher than the predetermined reference voltage VREF4 when the pixels PX11 to PXnm and the scan lines SL1 to SLn of the display panel 110 are not damaged. Accordingly, the detection signal output circuit 152_3 outputs the error detection signal DET having a low level.

The voltage of the detection signal SENSS1, which is the sum of the scan signals S1, S2, S3, and S4, becomes lower than the predetermined reference voltage VREF4 due to a leakage current when at least one of the pixels connected to the scan lines SL1 to SL4 or the scan lines SL1 to SL4 is damaged. In this case, the detection signal output circuit 152_3 outputs the error detection signal DET having a high level.

FIG. 13 is a timing diagram illustrating an operation of the error detection circuit shown in FIG. 11, according to another embodiment.

Referring to FIGS. 1, 11, and 13, the scan driving circuit 140 provide the scan lines SL1 to SLn with the scan signals S1 to Sn that transition sequentially to a low level during a scan period P2. In response to the fifth control signal CONT5, the error detection circuit 150_3 may detect whether the display panel 110 is damaged, during the scan period P2.

The voltage of the detection signal SENSS1, which is a sum of the scan signals S1, S2, S3, and S4, is maintained higher than the predetermined reference voltage VREF4 when the pixels PX11 to PXnm and the scan lines SL1 to SLn of the display panel 110 are not damaged. Accordingly, the detection signal output circuit 152_3 outputs the error detection signal DET having a low level.

The voltage of the detection signal SENSS1, which is the sum of the scan signals S1, S2, S3, and S4, becomes lower than the predetermined reference voltage VREF4 due to the leakage current when at least one of the pixels connected to the scan lines SL1 to SL4 or the scan lines SL1 to SL4 is damaged. In this case, the detection signal output circuit 152_3 outputs the error detection signal DET having a high level.

When the error detection circuit 150_3 detects the damage of the display panel 110, the pixel PXij illustrated in FIG. 2 may not include the second transistor T2 and the display 110 in FIG. 1 may not include the masking lines ML1 to MLn.

FIG. 14 is a flowchart illustrating an operation of the display device illustrated in FIG. 1.

Referring to FIGS. 1, 3 and 14, the scan driving circuit 140 provides the scan lines SL1 to SLn with the scan signals S1 to Sn including test patterns, during the test period Pt (S300). The scan signals S1 to Sn provided for the scan lines SL1 to SLn during the test period Pt may be pulse signals with the predetermined frequency. In other instance, as illustrated in FIG. 12, the scan signals S1 to Sn provided for the scan lines SL1 to SLn during the test period Pt may be pulse signals which are sequentially activated to a low level.

The scan driving circuit 140 provides, during the test period Pt, the masking lines ML1 to MLn with the masking signals M1 to Mn which have voltage levels complementary to voltage levels of the scan signals S1 to Sn (S310). For

example, when the i-th scan signal Si transitions to a low level, the i-th masking signal Mi transitions to a high level. Accordingly, even when the scan signal Si transitions to the low level during the light-emitting period P3, the data signal Dj received through the data line DLj may be prevented from being transmitted to the second node N2 in the pixel PXij illustrated in FIG. 2.

The error detection circuit 150 receives the scan signals S1 to Sn transmitted through the scan lines SL1 to SLn, and the masking signals M1 to Mn transmitted through the masking lines ML1 to MLn. The error detection circuit 150 compares the scan signals S1 to Sn and the masking signals M1 to Mn with a reference voltage (S320).

For example, as illustrated in FIGS. 4 and 6, the error detection signal DET is activated when the voltage of the sum of the i-th scan signal Si and the i-th masking signal Mi corresponding to each other of the scan signals Si to Sn and the masking signals Mi to Mn is lower than the reference voltage VREF (S330).

Alternatively, as illustrated in FIGS. 7 and 8, the scan driving circuit provides, during the test period Pt, outputs masking signals having the same waveform to the masking lines ML1 to MLn (S310) without supplying scan signals to the scan lines (no S300). The error detection signal DET is activated when the voltage of the sum of i-th masking signal Mi and the (i+1)-th masking signal Mi+1 is lower than a reference voltage VREF2 (S330).

Further alternatively, as illustrated in FIGS. 9 and 10, the scan driving circuit provides, during the test period, scan signals having the same waveform to the scan lines SL1 to SLn (S300) without supplying mask signals (no S310). The error detection signal DET is activated when the voltage of the sum of i-th scan signal Si and the (i+1)-th scan signal Si+1 is lower than a reference voltage VREF3 (S330).

Still further alternatively, as illustrated in FIGS. 11 to 13, the scan driving circuit provides, during the test period or during the scan period, scan signals that sequentially transition to a low level to the scan lines SL1 to SLn (S300) without supplying mask signals (no S310). The error detection signal DET is activated when the sum of four adjacent scan signals in less than a reference voltage VREF4 (S330).

In response to the error detection signal DET having a high level, the signal control circuit 120 may output the third control signal CONT3 such that the power voltage supply circuit 160 does not generate the first power voltage ELVDD and the second power voltage ELVSS. The operation of the display panel 110 is stopped when the power voltage supply circuit 160 does not generate the first power voltage ELVDD and the second power voltage ELVSS. Therefore, the display device 100 is protected against risks such as fire by preventing an overcurrent caused by a short circuit of the signal lines in the display panel 110.

By way of summation and review, according to one or more embodiments, a display device may detect whether a display panel is damaged. According to one or more embodiments, a driving method for the display device may detect whether the display panel is damaged.

Example embodiments have been disclosed herein, and although specific terms are employed, they are used and are to be interpreted in a generic and descriptive sense only and not for purpose of limitation. In some instances, as would be apparent to one of ordinary skill in the art as of the filing of the present application, features, characteristics, and/or elements described in connection with a particular embodiment may be used singly or in combination with features, characteristics, and/or elements described in connection with other embodiments unless otherwise specifically indicated.

11

Accordingly, it will be understood by those of skill in the art that various changes in form and details may be made without departing from the spirit and scope of the present invention as set forth in the following claims.

What is claimed is:

1. A display device, comprising:

a display panel includes:

a plurality of scan lines to receive scan signals,
a plurality of data lines to receive data signals, and
a plurality of pixels respectively connected to the
plurality of scan lines and the plurality of data lines;
and

an error detection circuit to receive the scan signals
transmitted through the plurality of scan lines, and to
output an error detection signal based on the scan
signals,

wherein power is not supplied to the plurality of pixels
when the error detection signal is at an activated level,
and

wherein the error detection circuit outputs the error detection
signal based on the scan signals during light-emitting
periods of the plurality of pixels.

2. The display device as claimed in claim 1, further
comprising a scan driving circuit to provide the scan signals
for the plurality of scan lines, wherein the scan driving
circuit is electrically connected to one end of each of the
plurality of scan lines, and the error detection circuit is
electrically connected to the other end of each of the
plurality of scan lines.

3. The display device as claimed in claim 2, wherein the
scan driving circuit provides the plurality of scan lines with
the scan signals including a test pattern during the light-
emitting periods of the plurality of pixels.

4. The display device as claimed in claim 3, wherein the
scan signals are a pulse signal with a predetermined frequency
during the light-emitting periods of the plurality of pixels.

5. The display device as claimed in claim 3, wherein the
scan signals are pulse signals which are sequentially activated
during the light-emitting periods of the plurality of pixels.

6. The display device as claimed in claim 5, wherein the
error detection circuit compares each of the scan signals
with a reference voltage, and activates the error detection
signal depending on the comparison result.

7. The display device as claimed in claim 2, wherein the
scan driving circuit and the error detection circuit face each
other with the display panel therebetween.

8. The display device as claimed in claim 1, wherein the
scan signals are pulse signals which are sequentially activated
during a scan periods of the plurality of pixels.

9. The display device as claimed in claim 1, further
comprising a plurality of masking lines corresponding to and
extending parallel to each scan line, wherein the error
detection circuit is to receive masking signals transmitted
through the plurality of masking lines, and output the error
detection signal based on at least one of the scan signals or
the masking signals.

10. The display device as claimed in claim 9, wherein
each of the masking signals has a level complementary to the
level of a corresponding scan signal among the scan signals
during the light-emitting periods.

11. The display device as claimed in claim 9, wherein
each of the plurality of pixels comprises:

a first transistor connected between a corresponding data
line among the plurality of data lines and a first node,

12

and having a gate electrode connected to a corresponding
scan signal among the scan signals;

a second transistor connected between the first node and
a second node, and having a gate electrode connected
to a corresponding masking signal among the masking
signals; and

a light-emitting circuit to receive a first power voltage and
a second power voltage, and to emit light according to
a voltage level of the first node.

12. The display device as claimed in claim 11, wherein the
light-emitting circuit includes:

a first capacitor connected between the first power voltage
and the second node;

a second capacitor connected between the second node
and a third node;

a third transistor connected between the first power voltage
and a fourth node, and having a gate electrode
connected to the third node; and

an organic light-emitting diode connected between the
fourth node and the second power voltage.

13. The display device as claimed in claim 12, wherein the
light-emitting circuit further includes a fourth transistor
connected between the third node and the fourth node, and
having a gate electrode connected to a compensation signal.

14. The display device as claimed in claim 9, wherein the
error detection circuit compares a sum of the scan signal and
the masking signal corresponding to each other with a
reference voltage, and activates the error detection signal
depending on the comparison result.

15. The display device as claimed in claim 9, wherein the
error detection circuit outputs the error detection signal
based on the masking signals during light-emitting periods
of the plurality of pixels.

16. A driving method for a display device including a
plurality of pixels connected to scan lines, the driving
method comprising:

providing the scan lines with scan signals;

providing masking lines with masking signals according
to the scan signals;

comparing at least one of a sum of the scan signals or the
masking signals corresponding to each other with a
reference voltage; and

activating an error detection signal based on the compari-
son result.

17. The driving method as claimed in claim 16, wherein
the scan signals provided for the scan lines are a pulse signal
with a predetermined frequency.

18. The driving method as claimed in claim 16, wherein
the scan signals provided for the scan lines are sequentially
activated.

19. The driving method as claimed in claim 16, further
including stopping power supply to the pixels when the error
detection signal is activated.

20. A driving method for a display device including a
plurality of pixels connected to scan lines, the driving
method comprising:

providing the scan lines with scan signals;

dividing the scan signals into a plurality of scan signal
groups;

comparing a sum of voltages of each of the plurality of
scan signal groups with a reference voltage, and
activating an error detection signal depending on the
comparison result.
